ALICE A. NICHOLSON, OF MELBOURNE, FLORIDA.

GAME APPARATUS.

1,248,892.

Specification of Letters Patent.

Patented Dec. 4, 1917.

Application filed October 2, 1916. Serial No. 123,362.

To all whom it may concern:

Be it known that I, ALICE A. NICHOLSON, a citizen of the United States, residing at Melbourne, in the county of Brevard and State of Florida, have invented certain new and useful Improvements in Game Apparatus, of which the following is a specification.

This invention relates to a game apparatus and more particularly to an apparatus to be used in the playing of a card game which will be educational and will at the same time require considerable thought and attention in the skilful playing thereof so that persons playing the game will not readily tire of the same.

An object of my invention is to provide apparatus for a card game which may be played by boys and girls or by grown persons, and which may be arranged as a progressive game in which total scores will be counted when a sufficient number of persons are playing, it being understood that the game might be played with the persons paired off as partners or with each person playing independently and counting his or her independent score.

A further object lies in the provision of a game apparatus which is based upon the arrangement of the stars in the field of a flag of the United States, the various cards being indicated by the names of the States which are represented by the stars of the flag and further indicated by numbers showing the particular position of the separate stars, and which game will thus prove educational in teaching the order of admission, or the order of application for admission of the various States to the Union, the character of the game being such that playing the same for any length of time will permanently fix the placing of the various stars in the mind of the player.

With the above and other objects in view, my invention consists in certain novel features of construction and combinations of parts which will be hereinafter set forth in connection with the drawings and then more particularly pointed out in the claims.

50 In the drawings:—

Figure 1 is an elevational view with the bracket inclosing a disclosure of the faces of a set of the cards embraced within a pack.

Fig. 2 is an enlarged view to better dis-

close the markings on the face of each of 55 the cards.

It is the intention that this game shall be played by two, four or more people, and where an equal number of people are playing together, they can take partners. 60

The game is played with a pack of cards, comprising two sets of cards numbered from 1 to 48 inclusive, one set being shown as an entirety in Fig. 1. The forty-eight cards of each set are to correspond to the forty-eight 65 stars placed in the field of the flag of the United States, and two sets of forty-eight each are to make up the complete pack.

As is better shown in Fig. 2, each card bears a five pointed star, preferably arranged with a point upward as the stars of the flag are placed, this star being preferably located at the center of the card as shown at 1. The cards each bear the name of one of the States of the Union as shown 75 at 2, and then the cards are numbered as at 3 to indicate the position which the star occupies in the field of the flag, it thus being seen that the star corresponding to each State is placed in the order of the State's 80 ratification of the Constitution and admission to the Union. For example, the two cards numbered "one" (1) that is the first card of each set, would bear the name of Delaware beneath the star, Delaware being 85 the first State to ratify the Constitution; the two cards numbered "two" (2) would bear the name of the State of Pennsylvania; "three," (3) New Jersey, and so on down to the newest State, Arizona, which is 90 star 48.

In addition to being numbered, each set of forty-eight cards is divided into six books of eight cards each, this division corresponding to the grouping of the stars as the same 95 are placed in rows when positioned in the field of the flag. Thus, book 1 contains cards 1 to 8 inclusive; book 2, cards 9 to 16 inclusive; book 3, 17 to 24 inclusive, and so on, the last being book 6, containing cards 100 41 to 48 inclusive. All of the cards in each of the six books are designated as is indicated at 4, so that they may be readily associated with the particular group or book in which they belong. 105

Rules of the game.

When there are four or more players they

- may divide themselves as partners, each player sitting opposite his or her partner, it of course being understood that where there are only two players each player will act and score individually, and that this same arrangement might be observed where a number of persons are playing, each player taking his hand against the remaining players and scoring individually.
- 10 The dealer deals five cards and then turns up one card from the pack for trumps. Players then bid for the advantage of leading, the players to the left of the dealer bidding first, and therearound from left to right, the dealer having the last bid.
- 15 A player need not bid if he holds low cards, and bids are to be computed on the understanding that each trick taken in counts 10, a player thus bidding 30 if he thinks he can take three tricks, 40 if he feels assured of four tricks, and 50 if assured of five tricks. When a player bids "fifty", another and subsequent player can bid higher or raise the bid only by bidding "fifty-fifty."
- 20 When bidding "fifty-fifty", and failing to win or take in five tricks, the bidder and his partner each lose fifty points, and the opponents each score fifty points. On straight bids or where "fifty-fifty" is not bid, opponents do not score if bidder fails to take the stated number of tricks except by the number of tricks taken from bidders and partners.
- 25 The highest bidder wins the advantage of leading. He takes up the turned up trump, discards his lowest card or some other card which he feels will not be of advantage to him, and begins the game by leading the highest card of his strong suit, or by
- 30 leading the card which will permit his partner to play back to advantage and to take the trick. Cards numbered 8, 16, 24, 32, 40 and 48 are the highest cards at the beginning of the game or until they have been taken in and retained, these being the highest cards of each book.
- 35 Following the playing of the first card by the party having the advantage of the lead, the players follow suit by playing a card of the book led. Only a higher numbered card of the book led, or a trump card, the trump cards being the eight cards of the book as indicated by the card turned up from the deck by the dealer, can win over the card led, and as there are two cards of each number, it is the card led or played first that wins the trick, should the duplicate cards come out or be played in a single round. Duplicate cards are thus ranked lower when
- 40 played as a forced card to follow suit, but retain their full rank under other circumstances.
- 45 From the tricks taken in, players retain one card of each set of 48 cards. Partners complete one of each six books of each set of cards, retained cards being placed on the table before the player, and all duplicate cards being discarded. Partners complete different books, each taking three of the six to be completed.
- 50 Discarded duplicate cards are shuffled and redealt, five at a time, until only cards enough for one hand are left. The last hand is the most important, and when this hand is dealt, each player should hold five cards, although the last hand can be played with any odd number from three to nine cards. The successful bidder for lead when the last hand is played takes up any odd cards left with the turned up trump, and if the cards come out even and there is no card to turn up for trump, the dealer names the trump before looking at his cards. The partners winning the last hand retain all the duplicates they themselves have taken in and receive all the discarded duplicates from tricks opponents may have taken.
- 55 The game is won when one side has taken in and retained forty-eight consecutive cards or one complete set, numbered from 1 to 48 inclusive.
- 60 *Scoring:*
- 65 A player who bids successfully for the lead, and his partner, each score fifty points when the stated number of tricks in accordance with the bid are taken, tricks above the stated number not being permitted for the bidder or his partner. Opponents of the successful bidder score five points for each trick taken, tricks taken by any player scoring only for the particular person who wins them, although partners assist each other to complete books.
- 70 When a player and his partner complete the six books of eight cards each, the game is won, the winning partners each scoring 300 points in addition to points already won.
- 75 *Penalty:*
- 80 Should a player retain two cards of the same number, or duplicate cards, he must when the mistake is discovered give up both cards, one to be discarded to be reshuffled with the remainder of the pack which is yet outstanding, and the other card to go to his opponent.
- 85 Further penalty shall be made in accordance with the statements as above, when a party bidding and having his bid accepted fails to make the requisite number of tricks, and additional scoring shall be entered for his opponent.
- 90 From the foregoing it will be seen that I have provided a pack of cards which may be used in the playing of a game in accordance with the rules as set forth and which will require the exercise of considerable care in skilful playing while at the same time the game will act to fix in the minds of the

players, the location of the various stars of the United States flag together with the particular grouping of the same in rows and to thus teach to the players the order of the ratification of the Constitution by and the admission to the Union of the various States, and while I have herein shown and described only one particular form which the cards might take, it will be understood that coloring of the cards or a varied arrangement of the printed matter thereon might be resorted to, and that other changes and modifications such as in the rules laid down for play with the pack of cards might be resorted to without departing from the spirit and scope of my invention, in view of which fact I do not wish to be limited to the exact disclosure but rather only to such points as may be set forth in the claims.

I claim:

1. A game apparatus comprising a book of eight cards having indicia representing the position of the stars in the first row of the field of the flag of the United States, each of said stars being marked to designate grouping thereof in the first book, and other books of cards clearly designated from the first book corresponding to the remaining rows of stars and marked to indicate the position of the stars represented thereby.
2. A game apparatus comprising a book

of eight cards having markings thereon to represent the position of the stars in the first row of the flag of the United States and also the States represented by the stars, each of said cards being marked to designate the grouping thereof in the first row, other books of cards designated from the first book and marked to designate the remaining rows of the stars of the flag, each of the cards of said last mentioned books having designations to show the particular State represented thereby and the position occupied by the star, and a duplicate card for each of the cards aforementioned.

3. A game apparatus comprising a pack of cards grouped off into six books of eight cards each, the cards of said books being designated to distinguish one book from another, indicating markings on the cards to designate the various States of the Union and the position taken by the representative star in the flag of the United States, and markings on said cards to indicate the representation of the stars of the flag.

In testimony whereof I affix my signature in presence of two witnesses.

ALICE A. NICHOLSON.
